UNITED STATES PATENT OFFICE.

FRANCIS A. McDONALD, OF ROCK ISLAND, ILLINOIS, ASSIGNOR TO SERVUS RUBBER COMPANY, OF ROCK ISLAND, ILLINOIS.

DESIGN FOR A RUBBER SHOE SOLE.

Application filed May 21, 1923. Serial No. 6,239. Term of patent 14 years.

To all whom it may concern:

Be it known that I, FRANCIS A. McDONALD, a citizen of the United States, residing at Rock Island, in the county of Rock Island and State of Illinois, have invented a new, original, and ornamental Design for a Rubber Shoe Sole, of which the following is a specification, reference being had to the accompanying drawing, forming a part thereof.

The figure of the drawing is a bottom plan view of a rubber shoe sole, showing my new design.

I claim:

The ornamental design for a rubber shoe sole, as shown.

In testimony whereof I affix my signature.

FRANCIS A. McDONALD
